UNITED STATES PATENT OFFICE.

JOHN PLAYER, OF TOPEKA, KANSAS.

COMPOUND LOCOMOTIVE.

SPECIFICATION forming part of Letters Patent No. 623,736, dated April 25, 1899.

Application filed January 24, 1898. Serial No. 667,728. (No model.)

To all whom it may concern:

Be it known that I, JOHN PLAYER, a citizen of the United States, residing at Topeka, in the county of Shawnee and State of Kansas, have invented certain new and useful Improvements in Compound Locomotives, of which the following is a specification.

My invention relates to that class of locomotives known as "compound" locomotives, in which the steam is admitted first into what is known as a "high-pressure" cylinder and afterward passes out of the same into a second cylinder, known as a "low-pressure" cylinder, in which it is allowed to expand and act on a piston of greater area and to compensate for its diminished pressure.

The invention has particular reference to the valve mechanisms by which the admission and exhaust of steam to and from the cylinders are controlled, and especially to the means for operating these valves, whereby one or both of the valves may be adjusted independently or simultaneously for the purpose of changing the travel of the valve, and thereby cutting off the steam at certain predetermined points.

The object of my invention is to provide a simple, economical, and efficient valve mechanism for compound locomotives whereby the travel of one or both of such valves may be changed independently or simultaneously, as desired; and the invention consists in the features, combinations, and details of construction hereinafter described and claimed.

In the accompanying drawings, Figure 1 is a vertical sectional elevation taken through the center of the cylinders; Fig. 2, a plan view of the mechanism for operating the slide-valves; Fig. 3, a sectional elevation taken on line 3 of Fig. 2; Fig. 4, a plan sectional view taken on line 4 of Fig. 1; Fig. 5, a modified form of the mechanism which connects the slide-valve with the rock-shaft for the purpose of operating the same; Fig. 6, a plan view of the mechanism shown in Fig. 5 with the slide-valves detached, and Fig. 7 an enlarged sectional view taken on line 7 of Fig. 5.

In illustrating and describing my improvements I will illustrate and describe those parts or portions only of a locomotive which I consider to be new, in connection with so much

of that which is old in the art as is necessary to disclose my invention and enable those skilled in the art to practice the same.

55

In constructing a locomotive in accordance with my improvements I use a high-pressure cylinder A and a low-pressure cylinder B, arranged in tandem relation to each other. These cylinders are provided with reciprocating pistons *a* and *b*, connected to a piston-rod A', which serves to connect both of the pistons with the cross-head B'. The cross-head is supplied with the usual connecting-rod, (not shown,) which connects it with the driving-wheels of the locomotive. (Shown in outline.)

In order to reciprocate the pistons by means of fluid under pressure, steam-chests C and D are provided for the high and low pressure cylinders, and each of such steam-chests is provided with what are known as "piston slide-valves" E and F, arranged in tandem relation and so that they cover and uncover the ports and exhausts *e* and *e'* and *f* and *f'* to admit and exhaust fluid under pressure from the cylinders. In order to operate these slide-valves and thereby control the admission and exhaust of fluid under pressure in the cylinders, a rocker-shaft G is provided, carrying a depending rocker-arm *g*, which in the usual instances is adjustably connected with "link" mechanism. (Not shown.) This rocker-shaft has an upwardly-projecting rocker-arm G', and secured to it is a bracket G². The slide-valve in the low-pressure cylinder is provided with a hollow valve-stem, through which is passed the valve-stem *e*² of the high-pressure slide-valve. The valve-stem of the low-pressure slide-valve is connected with the bracket G² on the upwardly-projecting rocker-arm, while the stem of the high-pressure valve is adjustably connected with the rocker-arm by means of the valve-rod *e*³.

95

As it is oftentimes necessary to vary the amount of fluid under pressure supplied to the high-pressure cylinder in order to compensate for the load or changes in grade, or, in other words, to change the travel of the high-pressure valve and cut off the initial fluid-pressure at predetermined points, I connect the valve-rod *e*³ adjustably with the rocker-arm by means of the strap H, which

100

encircles the rocker-arm and which is secured to it by means of the set-screw *h*, so that the position of the valve-rod, which is pivotally connected to the strap at *e*⁴, may be changed 5 on the rocker-arm and travel through an increased or diminished length of arc, and consequently change the travel of the high-pressure valve. It will be seen that the travel of the high-pressure valve may be regulated or 10 adjusted independently of the travel of the low-pressure valve, while the change of the engagement of the link with the lower depending rocker-arm changes the travel of both valves simultaneously.

15 In Figs. 5, 6, and 7 I have shown the same arrangement of slide-valves, but have shown a rock-shaft *J* provided with two upwardly-projecting rocker-arms *J'* and *J*² instead of one. In other respects the mechanisms are 20 essentially the same.

The advantages incident to a locomotive fitted with my improvements are that the travel of the high-pressure valve may be changed independent of the low-pressure valve and the 25 initial pressure fed to the cylinder regulated so as to compensate for an increased or diminished load or a possible ascending or descending grade.

I claim—

30 1. In a locomotive of the class described, the combination of high and low pressure cylinders arranged in tandem relation, a reciprocating piston in each cylinder, a cross-head, a piston-rod connecting the pistons with the 35 cross-head, a rock-shaft adapted to be connected with a movable part of the locomotive, a slide-valve for each cylinder arranged in

tandem relation and adapted to control the admission and exhaust of fluid under pressure to and from the cylinders, a hollow valve-stem for one of the slide-valves, a stem for the other slide-valve passed through the hollow valve-stem, valve-rods connecting the valve-stems with the rock-shaft, and means for adjustably connecting one of the valve-rods with the rocker-arm, substantially as described. 40

2. In a locomotive of the class described, the combination of high and low pressure cylinders arranged in tandem relation, a reciprocating piston in each cylinder, cross-head mechanism, a piston-rod connecting the pistons with the cross-head, a piston slide-valve for each cylinder arranged in tandem relation and by their reciprocations to admit or 50 exhaust steam under pressure to and from the cylinders, a hollow valve-stem for the low-pressure valve, a valve-stem for the high-pressure valve passed through the hollow valve-stem, a rocker-shaft adapted to be connected 55 with a movable part of the locomotive, a valve-rod connecting the hollow stem of the low-pressure valve with the rocker-shaft, and a valve-rod connected with the high-pressure-valve stem and adjustably connected with 60 the rock-shaft for the purpose of changing the travel of the high-pressure valve independent of the low-pressure valve, substantially as described. 65

JOHN PLAYER.
